UNITED STATES PATENT OFFICE.

WILLIAM DIEBEL, OF PHILADELPHIA, PENNSYLVANIA.

VENDING-MACHINE.

SPECIFICATION forming part of Letters Patent No. 768,271, dated August 23, 1904.

Application filed November 11, 1903. Serial No. 180,677. (No model.)

To all whom it may concern:

Be it known that I, WILLIAM DIEBEL, a citizen of the United States, residing at Philadelphia, county of Philadelphia, and State of Pennsylvania, have invented a certain new and useful Improvement in Vending-Machines, of which the following is a specification.

My invention relates to a new and useful improvement in vending-machines, and has for its object to provide a machine of this description and adapted especially for the sale of cigars, it being obvious, however, that it may be used for the sale of other articles with but slight alterations without changing the principle of the invention, as it is well known by persons versed in the art that machines of this class are operated by means of the insertion of a coin which releases certain locking mechanism, so as to permit the moving of the slide, which movement will bring one article within reach of the purchaser.

This invention deals particularly with the coin-actuating mechanism of the machine, the other features of the machine being applied for in separate application. The delivery-slide of this machine may be operated by hand, or it may be operated automatically by motor located in the machine. In the former case the coin-actuating mechanism will unlock the slide, so as to allow the same to be operated by hand, and will automatically lock the same after one article has been delivered. In a case where the motor is used the coin-actuating mechanism will release the motor and allow the same to operate until the slide has been driven to the rear by the motor to deliver the article and then returns to its normal position, when the motor will be automatically stopped by the coin-actuating mechanism.

In the drawings I have illustrated the machine as being operated by a motor; but it is obvious that the same mechanism could be utilized to lock and unlock the delivery-slide, which is actuated by hand, as shown in my former application for patent, Serial No. 122,319.

With these ends in view this invention consists in the details of construction and combination of elements hereinafter set forth and then specifically designated by the claims.

In order that those skilled in the art to which this invention appertains may understand how to make and use the same, the construction and operation will now be described in detail, referring to the accompanying drawings, 55 forming a part of this specification, in which—

Figure 1 is a vertical section through the machine, showing all the parts in their normal position; Fig. 2, a similar view to Fig. 1, showing the position of the parts after a coin 60 has been inserted; Fig. 3, a rear elevation of the interior of the machine; Fig. 4, a perspective view of the tilting coin-chute in its normal position; Fig. 5, a perspective view of the tilting coin-chute in the position of releasing the coin.

A represents the casing of the machine, the back A' of which is hinged, so as to open to gain access to the operating parts of the mechanism and to remove the money from the machine. The merchandise-holder is adapted to be held in the upper portion of the machine at B.

C is the delivery-slide, upon which the articles to be vended are adapted to rest, and one 75 article is adapted to fall in the pocket C' of the delivery-slide, which is normally closed at its lower end by the platform D, and when the slide is pressed rearward of the platform the article will fall out of the pocket C' into 80 a suitable merchandise-chute (not here shown) and be delivered to the exterior of the machine.

E is the motor which drives a crank E', to which a pitman F is connected, the other end 85 of the pitman being connected to the lower end of a lever G, pivoted at the point G', the upper end of the lever being pivoted to one end of a link H, the other end of the link H being pivotally connected to the delivery-slide 90 C, so that with each revolution of the crank E the delivery-slide is driven rearward and returned to its normal position.

E² is the governor of the motor, which may be in any form desired, here shown as a revolving blade.

I is the coin-chute, the coin being inserted at the point I'. This chute extends downward to a point below the delivery-slide and then turns at right angles and extends rear- 100

ward on a slight incline, the rearward opening being just above the tilting coin-chute J, this tilting coin-chute being formed of two parallel sides and a bottom and is pivoted to 5 the casing of the machine at the point J', the rearward end of this chute J being connected to one end of a spring K, the other end of the spring being connected to an adjustable strip K', this spring K being sufficiently strong to 10 hold the forward end of the chute J upward in its normal position, but said chute being so evenly balanced by the spring that when a coin passes the pivotal point J' in the chute the weight of the coin will be sufficient to 15 stretch the spring K and depress the forward end of the chute J, as shown in Fig. 2. Pivoted to the forward and rearward ends of the chute and extending laterally across the same are the strips L and L', respectively. These 20 strips form what I designate as "gates" and are adjusted to such a position that the proper-size coin cannot pass from the chute at either end until these gates are raised; but the adjustment is so fine that a coin slightly smaller 25 will pass underneath the gates, and a coin larger than the proper-size coin cannot be inserted in the machine on account of the opening I' being formed for just the proper-size coin. These gates L are normally held down 30 by the spring-arms M.

N is a shaft journaled to the chute below the same and extending longitudinally thereof. Each end of this chute has secured to it the upwardly-extending arms O and O', the upper end of these arms being bent or having 35 formed thereon cam-surfaces O², and when these cam-surfaces are brought in contact with the pins P, extending outward from the gates L, said gates will be raised.

Q is an arm secured to the shaft N, and the lower end of this arm turns at right angles and is arranged within the path of travel of a dog R, pivoted to an extension G² of the lever G. When the chute J is in its normal 40 position, the end Q' of the arm Q lies underneath the nose of the dog R, and when the forward end of the chute J is tilted downward by the weight of the coin and when the dog R travels forward and downward by the 45 movement of the lever G the nose of the dog R will pass the end Q' because of the fact that the dog R is free to turn upon its pivot, so that the nose may be rocked upward and pass the end Q'; but when the lever G begins 50 its return movement, and thereby raises the dog R, the upper surface of the nose of the dog will then be brought in contact with the under surface of the end Q' of the lever Q and will press upward upon said end Q' because of the fact that the dog is prevented 55 from turning downward on account of the pin R' limiting the movement in this direction, and therefore pressure will be exerted upon the outer end of the lever Q, which will 60 cause the shaft N to be rocked, and thereby 65

press the cam-surfaces O² into contact with the pins P, so as to raise the gates, and on a continued movement of the dog R upward the nose of the dog will snap past the end Q', and then the parts will resume their normal positions, as the spring K is then free to pull the chute J into its normal position, for the coin has been previously released by the raising of the gates. 70

S is a rod connected to the rearward end of the chute J, and the lower end of this rod is adapted to lie normally within the path of travel of the governor-blade E², so as to render the motor inoperative; but when the coin lies at the forward end of the chute J the rearward end of the chute is thereby raised and the rod S is pulled upward out of engagement with the governor-blade and remains so until the coin has been released by the raising of the gates and the dog R has passed above the end Q' of the lever Q. Then the spring K is free to act and in returning the chute J to its normal position causes the rod S to travel downward again, engaging the governor-blade and stopping the motor. 75 80 85 90

Thus it will be seen that the operation of the device is briefly as follows: The proper-size coin being inserted in the chute I will travel downward and pass into the chute J, and said coin would naturally with its impetus travel rearward in said chute and strike the forward gate L'; but said gate being down the coin could not pass underneath, and as the chute J is normally arranged on a slight incline forward the coin would then naturally roll toward the forward end of the chute and come in contact with the forward gate L, when this movement would be arrested and the weight of the coin would depress the forward end of the chute, and thereby start the motor by raising the rod S, and the coin would remain in the forward end of the chute until the article had been delivered and until the forward gate L had been raised, as before described. Then the coin would pass outward into the proper chute, which carries the same to the money-box of the machine. 100 105 110

If a coin slightly smaller in diameter than the proper-size coin is inserted in the machine, said coin being a little too large to pass underneath the gates, but still slightly undersize, such as a much-worn coin, said coin would be liable in passing rearward against the rear gate L' to press said gate upward slightly, so as to wedge underneath the same, and then of course the machine would not operate, and it would be required to insert a proper-size coin into the machine to operate the same, and the impact of this proper-size coin against the coin wedged underneath the gate would then act to either drive the worn coin underneath the gate into the chute T, where it could be conveyed either to the money-box or to the exterior of the machine, so as to be returned to the customer, or said 115 120 125 130

impact would drive the coin sufficiently farther underneath the gate so that when the gate was raised to release the proper-size coin at the forward end said worn coin would roll 5 out of the rear end into said chute T.

In order to cause the coin to roll rearward against the rear gate L' and also to allow the coin to enter the chute J at a uniform speed instead of dropping into the same, I provide 10 in the lower right-angle portion of the chute I a lever U, pivoted to the chute I at the point U', the forward end of said lever U being connected to a spring U², said spring being of such a strength that when the coin passes 15 rearward of the pivotal point U² it will depress the lever U into the position shown in Fig. 2, so as to allow the coin to enter the chute J with a rolling motion instead of dropping abruptly into the same.

20 V is a lever pivoted in the upper portion of the chute I, said lever being provided with two arms V' and V², the arm V' normally closing the chute I on account of the weighted portion V³ of the lever holding said arm 25 in this position; but when a coin is inserted in the chute and drops upon the arm V' said arm will be pressed downward, thus bringing the end of the arm V² into contact with the forward wall of the chute I above the coin 30 and allowing the coin to pass the arm V' and travel onward down into the chute. Thus if a string or thread is attached to the coin for the purpose of removing the coin after it has 35 actuated the machine said string or thread will be caught between the end of the arm V² and the forward wall of the chute I, and thus prevent any further downward movement of the coin, and then the spring must be pulled upon, so as to pull the coin upward, before 40 the machine can again be operated.

W is a short crank secured to the shaft N upon the chute J, and to the outer end of this crank is attached a rod X, which extends upward and is then bent so as to extend over the 45 top of the chute. If two or more coins, one after the other, should be dropped into the machine before the machine has operated once, this rod X when the shaft N is rocked by the arm Q would pass behind the coin about 50 to be released and in front of the next coin just behind the coin to be released, and thus hold the other coins back until the forward coin had been released and the gate N has resumed its normal position. This would prevent 55 more than one coin passing out of the machine at a time and allow the customer to receive articles for each coin deposited.

Of course I do not wish to be limited to the exact construction here shown, as slight modifications could be made without departing from the spirit of my invention.

Having thus fully described my invention, what I claim as new and useful is—

1. In a coin-actuated vending-machine, the 65 combination of a stationary coin-chute and de-

livery-slide with a tilting coin-chute, said tilting coin-chute pivoted to the casing, a spring secured at one end to one end of the tilting coin-chute, the other end of the spring adjustably secured to the casing of the machine, said 70

spring adapted to hold the other end of the tilting chute upward in its normal position, the weight of the coin, when said coin rolls to the other end of the chute opposite the spring, adapted to depress this end of the chute against 75 the action of the spring, a gate located at the end of the chute opposite that end to which the spring is connected and arranged in such a position that normally it will prevent the proper-size coin from rolling out of that end 80 of the chute, but allow a smaller-size coin to pass underneath the gate, a spring normally holding the gate downward, mechanism controlled by the tilting chute allowing the delivery-slide to pass rearward and deliver the 85 article to be vended when the chute is tilted by the weight of the coin, and also allow the delivery-slide to return to its normal position, means for raising the gate and allowing the coin to pass from the tilting chute when the 90 delivery-slide is returning to its normal position, as and for the purpose specified.

2. In a coin-actuated vending-machine, a casing, a delivery-slide, a stationary coin-chute, a tilting coin-chute arranged to receive 95 the coin from the stationary chute, said tilting chute pivoted on a horizontal pivot at a point intermediate between its two ends and normally inclined forward and downward from the end where it receives the coin, a 100 spring connected at one end to the rearward end of the tilting chute and at the other end to an adjustable strip secured to the casing, gates pivoted at each end of the tilting chute and extending laterally across above the same, 105 said gates so arranged that when in their normal position they will not allow a proper-size coin to pass underneath the same, but will allow a coin to pass underneath that is slightly smaller in diameter, springs adapted to hold 110 the gates downward in their normal position, a motor, a lever extending from the motor to the delivery-slide for operating said slide, a governor for governing the motor, a rod extending downward from the rear end of the 115 tilting chute in the path of travel of the governor to normally hold the motor inoperative, the weight of the coin after passing forward of the pivotal point of the tilting chute adapted to press the forward end of the chute against 120 the action of the spring and thereby raise the rod out of engagement with the governor and allow the motor to cause the slide to travel rearward and back again to its normal position, mechanism whereby the returning 125 of the delivery-slide to its normal position will raise the gates and allow the coin to pass from the tilting chute and thereby allow the spring to act to return the tilting chute to its normal position and cause the rod to again 130

engage the governor and stop the motor, as specified.

3. In a coin-actuated vending-machine, the combination of a casing, a delivery-slide and 5 a stationary coin-chute with a tilting coin-chute adapted to receive the coin from the stationary chute, said tilting chute being pivoted intermediate of its two ends upon a horizontal pivot to the casing and arranged upon 10 a slight incline downward and forward, a spring secured to the rearward end of the chute and adapted to normally hold the forward end of the chute upward, the coin when entering the tilting chute adapted to roll forward, and when forward of the pivotal point of the coin will depress the forward end against the action of the spring, gates pivoted at each 15 end of the tilting chute and extending laterally across the same, said gates when in their normal position preventing the coin from leaving the ends of the chute, springs for holding the gates downward, a shaft journaled underneath and to the tilting chute extending longitudinally of the same, arms connected 20 to the shaft at each end and extending upward therefrom, pins extending outward from the gates, said arms adapted to come in contact with said pins when the shaft is rocked so as to raise the gates, a lever secured to the 25

shaft and extending downward therefrom, 30 the lower end of the lever bent at right angles and extending outward, a motor, a lever pivoted intermediate of its two ends, the lower end of the lever connected to the motor, the upper end of the lever connected to the delivery-slide, an arm extending outward from said lever above the pivotal point, a dog pivoted upon the outer end of said arm, said dog adapted to come in contact with the outer end of the lever connected to the shaft on the 40 tilting chute so as to rock said shaft and raise the gates, an arm extending upward from said shaft and adapted to pass between the coin about to be released and any coins behind the same when the shaft is rocked so as to 45 hold the rearward coins from passing outward with the forward coin, and means for starting the motor when the chute is tilted downward and stopping said motor when the chute returns to its normal position, as specified. 50

In testimony whereof I have hereunto affixed my signature in the presence of two subscribing witnesses.

WILLIAM DIEBEL.
